CLAIM

What is claimed is the ornamental design for a handguard for a firearm, as shown and described.

DESCRIPTION

FIG. 1 is an top, rear, left-side perspective view of a handguard for a firearm showing my new design.

FIG. 2 is a bottom, front, right-side perspective view of the handguard for a firearm of FIG. 1.

FIG. 3 is a rear elevational view of the handguard for a firearm of FIG. 1.

FIG. 4 is a front elevational view of the handguard for a firearm of FIG. 1.

FIG. 5 is a top plan view of the handguard for a firearm of FIG. 1.

FIG. 6 is a bottom plan view of the handguard for a firearm of FIG. 1.

FIG. 7 is a left-side elevational view of the handguard for a firearm of FIG. 1; and,

FIG. 8 is a right-side elevational view of the handguard for a firearm of FIG. 1.

The broken lines in the figures depict portions of the handguard for a firearm that form no part of the claimed design. The dot-dash broken lines represent symbolic break lines and a bracket that forms no part of the claimed design. The area between the symbolic break lines forms no part of the claimed design.
